Patented June 7, 1921.

FIG. 1.

FIG. 2.

FIG. 3.

Inventor:
Mark Thomas Denne
per *H. J. Morris*
Attorney.

UNITED STATES PATENT OFFICE.

MARK THOMAS DENNE, OF RUSHDEN, ENGLAND.

WIRE-FEED MECHANISM OF SCREWING-MACHINES.

1,380,538.

Specification of Letters Patent. Patented June 7, 1921.

Application filed October 22, 1919. Serial No. 332,550.

To all whom it may concern:

Be it known that I, MARK THOMAS DENNE, a subject of the King of Great Britain and Ireland, residing at Rushden, Northamptonshire, England, have invented new and useful Improvements in and Relating to Wire-Feed Mechanism of Screwing-Machines, of which the following is a specification.

This invention has reference to improvements in and relating to wire feed mechanism of screwing machines—such as are employed for, *inter alia*, attaching the soles of boots and shoes—and in particular to that type of such mechanisms in which several pivoted feed dogs or grippers are first made to grip the wire and thereafter to feed it.

My invention consists in a device (for example a "floating" ring that surrounds the usual hollow spindle) which will adjust itself so that all the feed dogs will act to an equal extent in gripping and thereafter feeding the wire. The provision of such a device is very desirable because, apart from inequalities in the wire, there are sometimes imperfections in manufacture of the several parts associated to grip the wire and the result of this is that the wire is gripped unequally, or in some cases eccentrically since the gripper which is farthest from the axis of the spindle will receive the pressure of the wire and in so doing determine its eccentricity. This is very detrimental to proper working of the machine, having regard to the great strain on the wire when it is being screwed into the work at a high speed, and it often causes mysterious breakages.

A diagrammatic illustration of a simple constructional form of my invention is given by way of example in the accompanying drawing, in which:

Figure 1 is a side elevation, partly in section, of the spindle of a screwing machine provided with gripper closing means in accordance with the invention.

Fig. 2 is a section on the line A, B, of Fig. 1 showing the gripper closing means only, and

Fig. 3 is a section on the line C—D of Fig. 1, showing how the grippers coöperate in gripping the wire.

In said drawing *a* indicates a hollow spindle the lower end of which has an aperture *b* to receive the shank of a nozzle (not shown) through which spindle and nozzle the screwed wire *c* passes. Rotating with

and adapted to be reciprocated vertically with respect to the spindle *a* is a sleeve *d* which carries pivotally the feed dogs or grippers in the usual manner.

60

In accordance with the particular constructional form of my invention illustrated I provide a "floating" ring or collar *f* which is supported so as to move in the vertical direction with a sleeve-like yoke *e* but which has its inner diameter sufficiently large that it may move in any direction in a plane at right angles to the axis of the spindle *a*. A convenient way to support the collar thus is to form the yoke *e* with a groove *i* and the collar with a groove *h* and to fit blade springs *j* in said grooves the center part of the springs resting in the groove of the yoke and the ends of the springs projecting into the groove of the collar about as shown. 75 The springs are of a sufficient width to support the collar securely but are fairly thin so that although they will tend to maintain the collar concentric with the yoke they will not offer much resistance to movement of 80 the collar in a horizontal direction but will yield readily to permit of the ring taking up an eccentric position relatively to the yoke. If desired each spring may have a central pin *k* that enters an aperture in the 85 yoke.

75

The lower end of the sleeve carries three feed dogs or grippers *l*, mounted on pins *n*. Each gripper has a lug or wing *m* extending outwardly and upwardly from it, the 90 free end of which is formed with an inclined plane *m*¹ with which the lower and preferably rounded end of the collar *f* engages when the yoke *e* moves downward relatively to the sleeve *d*.

95

When the machine is in operation, as the yoke descends the collar *f* contacts with one or more or all of the inclined planes *m*¹ and thereby swings the relative gripper or grippers into contact with or toward the wire. 100 If, for example, only one of the grippers is in contact with the wire, further downward movement of the yoke will not act to cause the said grippers to feed the wire but will cause the collar to be moved in a horizontal direction until the inclined plane *m*¹ of each of the wings *m* becomes engaged to an equal extent, *i. e.*, until the collar exerts an equal pressure on all the wings and consequently all the grippers will be exerting an equal pressure against the wire. The collar therefore automatically beds itself on

105

110

the wings so that all the grippers will be brought to that position relatively to the wire where they will all act to an equal extent in gripping and thereafter feeding the 5 wire.

What I claim is:

1. Wire feed mechanism for screwing machines, comprising in combination a hollow spindle through which the wire passes axially, a gripper carrier adapted to be reciprocated longitudinally of the said spindle, a plurality of grippers mounted on the said carrier, and means for closing the said grippers on the wire adapted to be reciprocated 10 on the said spindle relatively to the said gripper carrier and to adjust itself automatically in any direction in a plane at right angles to the axis of the spindle to cause each of the grippers to exert an equal pressure 15 on the wire.
2. Wire feed mechanism for screwing machines, comprising in combination a hollow spindle through which the wire passes axially, a sleeve which is slidable longitudinally 20 on the said spindle, a plurality of grippers

mounted on the said sleeve, a sleeve-like yoke which surrounds the said sleeve and is slidable thereon, a gripper closing member in the form of a ring which surrounds the said yoke loosely, and yielding means interposed 30 between the said ring and yoke adapted to hold the said ring normally concentric with the said yoke but capable of yielding readily to permit of the ring taking up an eccentric position relatively to the yoke for the purpose set forth.

3. In wire feed mechanism of screwing machines, the combination with a hollow spindle through which the wire passes axially and a plurality of grippers carried on 40 the said spindle and adapted to grip and feed the wire, of gripper closing means consisting of a floating ring surrounding the spindle and adapted to adjust itself automatically in any direction in a plane at right angles to 45 the axis of the spindle, and movable longitudinally of the spindle to force the grippers into engagement with the wire.

MARK THOMAS DENNE.
